ACOUSTIC DEVICE

Filed April 1, 1926

UNITED STATES PATENT OFFICE

SPENCER W. MCKELLIP, OF PHILADELPHIA, PENNSYLVANIA, ASSIGNOR TO WIRT COMPANY, OF GERMANTOWN, PENNSYLVANIA, A CORPORATION OF MAINE

ACOUSTIC DEVICE

Application filed April 1, 1928. Serial No. 98,987.

My invention relates to a novel construction of an acoustic device or instrument adapted to be vibrated to reproduce sounds, and to which the vibrations may be imparted by a loud speaker electromagnetic element, the arrangement of the instrument being such that the original sound waves or vibrations transmitted to the driving element so as to substantially correspond in amplitude, pitch and timbre to the original sound waves without distortion.

By my novel device the vibrations produced by the driving device or electromagnetic element are directly transmitted by a floating tympanum, cone or conical shaped body in such a manner that the latter excites directly in the surrounding free air, sound waves of an intensity and amplitude substantially corresponding to the original sound waves.

My invention in its broad aspects consists in the provision of a novel floating tympanum or conical body of novel construction and having its free or large end loosely held by but disconnected from a support, whereby the side walls of said cone may accurately respond to the high frequency vibrations employed in the reproduction of sounds and imparts said vibrations to a relatively large body of unconfined air. In carrying out my invention, I employ a novel construction of a floating cone which has its apex reinforced in a novel manner and has its forward or open end provided with an annular, peripheral, reversely inclined, continuous integral lip or flange, said tympanum or cone being constructed of light vibratile material having considerable rigidity within itself, such as hot pressed paper, fiber, compressed fibrous material, parchment, thin animal skin or any other similar membrane capable of producing the desired results. I further construct my novel floating cone, so that the latter as a whole will be extremely light and have as little inertia as possible without a weakening effect.

In carrying out my invention I mount the reproducer with an adjustable connection between it and the driving element and

seat its periphery against a yielding cushion in such a manner that it is entirely free and unconfined.

With the above ends in view, my floating cone member is provided with an apex reinforced in a novel manner, while the opposite or free end of the cone is provided with a reversely inclined, annular, peripheral flange faced at its front surface with a felt annulus, the latter being adapted to contact with and be centered in the bevelled wall of a stationary felt annulus supported in any convenient manner, as in the front of a cabinet, the latter if desired being provided with a grille having a facing of silk or other material behind said grille.

My invention further consists of other novel features of construction, all as will be hereinafter fully set forth and pointed out in the claims appended hereto.

For the purpose of illustrating my invention I have shown in the accompanying drawings the preferred form thereof, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings:—

Figure 1, represents a perspective view of an acoustic device, embodying my invention, inclosed in a suitable cabinet.

Figure 2 represents a vertical section on line 2—2 Figure 1.

Figure 3, represents on an enlarged scale a sectional view of the outer peripheral portion of the floating cone, showing the reversely inclined annular peripheral flange, the felt attached thereto and the coacting stationary felt annulus.

Figure 4, represents on an enlarged scale a sectional view of the apex of the cone, its reinforcing devices and the means for adjusting it relatively to the driving element.

Figure 5, represents on a reduced scale a front view of the apex of a cone.

Referring to the drawings in which like reference characters indicate like parts, 1 designates my novel construction of a conical sound reproducer or acoustic device, the 5 same comprising the conical body 2 of paper, parchment or other material, having the apex 3, and the opposite open floating end, having its outer peripheral, reversely inclined flange 4, whose outer surface is faced with or has 10 secured thereto the annulus or annular felt ring 5. 6 designates a stationary felt ring or annulus having the inner bevelled wall 7 of the same inclination as the floating felt annulus 5, said annuli 5 and 6 being disconnected but in contact as seen in Figures 2 and 3. The front wall of the annulus 6 is secured to the front plate 7* and the opening 8 through said plate 7* is substantially the same diameter as the opening 9, through the 15 stationary felt annulus 6, which latter is relatively thick and forms a cushioned body against which the floating annulus 5 contacts. Through the apex 3 of the cone passes the threaded stem 10 of the head 11, which 20 has the axial passage 12 therethrough for the reed 13, which is held in the desired position by the set screw 14. 15 designates a cone shaped washer positioned at the inner apex of the cone 2, which is held in position by the nut 16 engaging the threaded stem 10. The outer portion of the cone at its apex is reinforced by the thin sheet metal star 17 having the radiating arms 18. This construction gives the necessary reinforcement 25 to the outer apex of the cone, with a minimum amount of metal. The front plate 7* may be secured in the front of a suitable cabinet 19, having an open front in which is the removable grille 20, seated in the upper 30 and lower grooves 21 and 22, said grille having behind it the sheet of silk or other fabric 23, seen in Figure 2, but omitted from Figure 1 for clearness of illustration. The rear of the cabinet as at 24 is open so that 35 there is no confined body of air on either side of the cone to retard or dampen the vibrations thereof.

A very satisfactory regeneration of sounds from the sound vibrated element will be 40 had and the volume thereof may be governed by increasing or decreasing the diameter of the floating annular peripheral flange and the diameter of the apertures 8 and 9.

The altitude of the conical portion 1 may 45 likewise be varied with the diameter to produce the desired pitch of fundamental notes.

In practice I prefer to cement the parts 50 17 and 15 to the apex of the cone by preferably a suitable acetone cement, and I also 55 prefer to braze or solder the joint between the star 17, and the head 12 at about the point 19 so that the apex of the cone will be tightly and rigidly clamped in position between the parts 17 and 15, so that all the 60 above mentioned elements vibrate as a unit.

In the formation of the floating cone, after blanking out the cone body from paper or other material, I score or crease the same on about the line 20 (see Figs. 2 and 3) and then bend the flange 4 into the position shown, whereby an integral peripheral reinforcement is formed which forms a convenient facing on which to mount the felt strip 5, and affords the latter sufficient width to form a seat against the cooperating felt ring 6. One object in providing an appreciable area of contact between the two felt rings resides in the fact that the fibers of the two felt pieces interlock, and without appreciable pressure between them it is possible to support the entire weight of the cone and thus relieve the reed 13 from any lateral displacement.

By the collocation of the stationary, relatively thick felt annulus 6, having its bevelled edge 7 facing and contacting with the inclined floating front annulus 5, said stationary annulus serves at all times as centering means for the free floating end of the cone 1, and so retains it at all times that it is flexible and may move in any direction in accordance with vibrations imparted to it by the reed 13. This arrangement of the parts renders the cone extremely responsive and sensitive at all times to the minutest vibrations and said reed, so that the reproduced sounds are regenerated in and by said cone with remarkable fidelity to the original sound waves. While I have described the annuli 5 and 6 as being preferably of felt, it will be understood that other similar or equivalent materials may be employed, although I have attained the best results from felt annuli. Especial attention is called to the fact that the free end of my novel cone is entirely unsupported in the sense that it is not rigidly attached or secured in any manner to outer rings or other extraneous supporting devices to a support, the vibratile material of which the cone is constructed is free to respond throughout to the movements imparted by the reed or driving element, and at the same time the free edge of the cone is damped against movement imparted to it by low frequency vibrations beyond the point where discordant notes will be created.

Having thus described my invention, what I claim as new and desire to secure by Letters Patent, is:—

1. An acoustic device comprising a support having an opening and a ring of yielding material surrounding it and forming a cushion, of a cone of vibratile material having an edging of similar material resting against the cushion and means for vibrating the cone.

2. An acoustic device comprising a support having an opening and a felt ring surrounding it, of a vibratile cone having a felt

binding strip on its free edge contacting with said ring, and means for vibrating the cone.

3. An acoustic device comprising an apertured support, a felt ring surrounding the aperture and beveled outwardly therefrom, of a cone of vibratile material having a flange on its free edge similarly beveled and provided with a strip of felt fitting within the inclined surface of said ring, and means for vibrating said cone.

4. An acoustic device comprising a cone of vibratile material having its open end provided with an annular reversely inclined flange, a support, cushioning means positioned between the flange and the support, and means to vibrate the cone.
